FREDERICK F. CORNELL, JR., OF NEW YORK, N. Y.

Letters Patent No. 61,717, dated February 5, 1867.

IMPROVED BEATER IN BALING PRESS.

The Schedule referred to in these Letters Patent and making part of the same.

TO ALL WHOM IT MAY CONCERN:

Be it known that I, FREDERICK F. CORNELL, Jr., of the city, county, and State of New York, have invented certain new and useful improvements in Baling Presses, of which the following is a full and accurate description; reference being had to the accompanying drawing, making part of these specifications, and in which—

Figure 1 is an elevation of said improved press, taken in the line xx of fig. 2

Figure 2 is a vertical section, taken in the line yy of fig. 1; and

Figure 3 is a horizontal section, taken in the line zz of fig. 1.

The like letters in each of the figures refer to the same parts.

In constructing this improved lever beater baling press, I provide two short pairs of sills, E E, which each contain a sheave, F F', designed to deliver to the capstan the ropes J and I from the beater B and levers L L respectively. On and at right angles to these, I place the main sills D D of the press which support the superstructure, and at each end receive the through pins $r r$ on which the tension-rods A A A A of the levers play. Upon these sills I erect the posts G G G G of the press-chamber, which is constructed in the same manner as that in the "Harris Beater Press." These posts, at the narrow ends of the press, are tied together by the caps N N, on which rest the posts which support the cap containing the wheel M to carry the rope J, and receive between them the sheaves H H H to carry the rope I, and whose inner faces are provided with the track $eeee$ to control the beater in its movements. This track is continued down and into the press-chamber, as shown at $e' e' e' e'$, and retains the beater in position by engaging with the grooves $ffff$ in the narrow ends thereof. The beater B may be constructed in the same manner as that used in the "Harris Beater Press," or in any other convenient form, and is also provided with pressure arms C C, whose lugs $c c$ are clawed so as to clasp loosely at either end the ropes I and J, which, by such new arrangement, may be carried down within the framing of the press, as distinctly shown, and the upper faces of said lugs $c c$ are provided with concavities to fit the segments of the shanks of the levers L L, as hereinafter described. The levers L L are placed one at either end of the press, and play freely on their centre pins $a a$, by which they are attached to their tension-rods A A A A. Their lower ends or shanks $b b$ are provided with a segment of a circle to articulate with the concavity in the pressure arms C C, when the beater B is used as a follower; said segments have pins $o o$ passing through their centres at right angles to the levers which engage with the guards $d d d d$ attached to the posts G G G G, and which are of a length corresponding to the extent of the motion of the shanks of the levers, and which are designed to keep said shanks at all times in a position to articulate with said pressure arms when forced out to engage therewith for the purpose of compressing the bale. Said levers are operated by the rope I, which is permanently attached at the point q , and passed over the sheaves K K, H H H, and F', and through the slot c in the lug of the pressure arm C, and between the shank b , the posts G G, and the lining m . The beater rope J is carried down within the framing of the press in a similar manner. The press is provided with the ordinary sheeting, bale, and feed doors and grooves in beater face, and sills to receive the straps for fastening the bale.

The operation of this improved press is as follows: The material being first filled into the press-chamber by the action of the beater in the ordinary manner, the pressure arms C C are forced out under the shanks $b b$ of the levers L L, which assume a horizontal position of their own weight when the rope I is slack, but when the rope is drawn upon, it causes the outer ends of said levers to rise, and the segments of the shanks of said levers, articulating with the concavities in the lugs $c c$ and bearing thereon, communicate motion to the beater B, then operating as a follower by which the bale is packed. The doors are then opened, and the bale hooped in the usual manner. By then slackening on the rope I, and drawing on the rope J, the shanks $b b$ will rise in the guards $d d$, and the arms C C, being drawn upon by the rods P P connecting with the rope J, will swing inwards, and the beater will rise off the bale, which may then be removed from the press.

What I claim as new and as my invention in the above-described press, are—

1. Forming the grooves or slots $ffff$ in the ends of the beater B, and providing the inner faces of the narrow ends of the press-chamber with the track $e' e' e' e'$, and continuing the same upon the inner faces of the superstructure, for the purposes herein described.
2. Forming the slots $c c$ in the ends of the pressure arms C C, through which the ropes I and J may play freely.

3. Carrying the ropes I and J, one at either end, down within the framing of the press between the posts G G G, sheeting *m m*, and shanks *b b*.

4. The levers L L, segmented shanks *b b*, shank pins *o o*, guards *d d d d*, and concave lugs of pressure arms C C, all combined and arranged for the purposes hereinbefore specified.

5. The rope I, sheaves K K, H H H, and F, arranged to operate and control the levers L L, as described.
